A. G. GULBRANSEN.

BELLOWS CONSTRUCTION FOR PLAYER PIANOS AND THE LIKE.

APPLICATION FILED OCT. 25, 1918.

1,356,710.

Patented Oct. 26, 1920.

UNITED STATES PATENT OFFICE.

AXEL G. GULBRANSEN, OF CHICAGO, ILLINOIS, ASSIGNOR TO GULBRANSEN-DICKINSON CO., OF CHICAGO, ILLINOIS, A CORPORATION OF ILLINOIS.

BELLOWS CONSTRUCTION FOR PLAYER-PIANOS AND THE LIKE.

1,356,710.

Specification of Letters Patent. Patented Oct. 26, 1920.

Application filed October 25, 1918. Serial No. 259,615.

To all whom it may concern:

Be it known that I, AXEL G. GULBRANSEN, a citizen of the United States, residing at Chicago, in the county of Cook and State 5 of Illinois, have invented a certain new and useful Improvement in Bellows Construction for Player-Pianos and the like, of which the following is a full, clear, concise, and exact description, reference being had 10 to the accompanying drawings, forming a part of this specification.

My invention relates to the bellows construction for player pianos and the like and particularly to the pumping bellows which 15 are employed to create the suction by which the player piano is operated.

The suction bellows as heretofore constructed have generally employed a spring for moving the movable board inward and 20 pedal means or some other operating device is connected to the movable board for distending the bellows to create the suction.

Heretofore in the operation of these devices the rubbing of the spring against the 25 movable board of the suction bellows has often caused a very annoying squeak or noise.

Such noise is almost impossible to eliminate and is very undesirable.

30 The aim of the present invention is to provide a noiseless and efficient bellows for devices of this class.

In order to acquaint those skilled in the art with the preferred manner of practising my invention, I shall now describe, in 35 connection with the accompanying drawings which form a part of the present specification, an embodiment of my invention.

Figure 1 is a perspective view of the main 40 wind channel with the supporting board for the equalizer bellows and the pumping bellows of a typical player piano mechanism;

Fig. 2 is a fragmentary front elevation 45 of the suction bellows of my invention showing the manner in which the spring and roller co-operates; and

Fig. 3 is an end view taken from the right of Fig. 2.

50 The pumping bellows 1 and 2, which are similar in construction, are mounted upon a supporting board 3 and a wind channel 4, as is customary in structures of this character. Each bellows consists of a movable board 5 and a stationary board 6 connected

together by means of a flexible wall 7, preferably made of leather. The interior of the pumping bellows 1 and 2 communicates with suitable passageways in the wind channel 4 and these passageways connect in turn with the equalizer or reservoir bellows 8 and 9, the construction of which is well understood. These equalizing or reservoir bellows are also mounted upon the baseboard 3 and communicate with the interior of the wind channel 4. Upon the interior of each of these bellows 8 and 9, spring means is provided for holding the bellows normally in suspended position, and when suction is created in the passageways of the wind channel 4 by means of the exhauster or pumping bellows 1 and 2, the equalizing or reservoir bellows 8 and 9 are collapsed against the tension of their respective springs in order to smooth out the fluctuation pressure which might otherwise be caused by the irregular operation of the bellows 1 and 2. The bellows 1 and 2 are operated preferably by suitable pedal mechanism which is indicated by the brackets 10 secured to the movable board 5. The exhauster or pumping bellows 1 and 2 are provided with leaf springs 11 which tend normally to collapse these bellows so that they may be distended for pumping purposes by the power applied at the pedals. The leaf springs 11 are L-shaped, one arm of the L being fastened by the screw 12 and the strap 13 to the top of the wind channel 4. The free end or other leg of the spring 11 extends down and is curved upwardly to a slight extent as shown at 14 at the point where connection is made between this free end of the spring and the exhauster or pumping bellows. A small friction plate 15 which may be stamped out of sheet metal is secured to the movable board 5 directly under the end of the spring 11. This friction plate 15 is provided with small lugs at the end through which suitable holes are formed to permit fastening of the friction plate by means of the brads or nails 16. A small anti-friction roller 17 is interposed between the end 14 of the spring 11 and the friction plate 15. This roller substitutes rolling friction for sliding friction which is the cause of the squeak and noises in piano constructions heretofore employed.

The upper and lower edges of the friction plates are turned up to form flanges as

shown at 18 and 19 so that the anti-friction roller 17 may be invariably retained between the friction plate 15 and the spring 11, and may be guided against assuming a 5 skewed position.

The result of this construction is a quiet bellows and one in which the friction of the engagement between the spring and the movable board is a minimum.

10 It is to be understood that I do not intend to limit my invention to the precise details shown and described.

I claim:

15 1. In combination, a bellows having a stationary board and a movable board, a support for the stationary board, a leaf spring having one end mounted on said stationary board and having a free end operatively engaged with the movable board of the bell-

20 lows, said connection comprising a friction plate mounted on the movable board and a roller engaging the friction plate and the free end of the spring.

25 2. In combination, a wind channel, a bellows having a stationary board secured at its upper end to said wind channel, a movable board, an L-shaped leaf spring having one end secured to the wind channel and having its free end extending over the mov- 30 able board of the bellows, a friction plate mounted on the movable board and an anti-friction roller lying between the friction plate and the free end of the spring.

35 3. In combination, a bellows having a stationary board and a movable board, a metal-

lic plate mounted on the movable board, said plate having its upper and lower edges upturned at substantially right angles to the body of the plate, a spring for moving the movable board, and a roller lying in contact 40 with the plate and with the spring, said roller being restrained by said upturned flanges.

4. In combination, a bellows having a stationary board and a movable board, 45 spring means for engaging the movable board, a small metallic plate mounted on the outside of said movable board, said spring means extending over said plate, and an anti-friction roller lying between said 50 spring means and said plate, said plate having flanges for restraining the movement of the roller.

5. In combination, a wind channel, a supporting board connected to said wind channel, a bellows mounted on the wind channel and on said board, said bellows comprising a stationary board and a movable board, a leaf spring of L-shape having one edge thereof connected to the wind channel, a 60 metallic strap lying over the said one end of the spring, the other end of the spring being operatively engaged with the movable board of the bellows and an anti-friction roller interposed between said end of the spring 65 and the movable board of the bellows.

In witness whereof I hereunto subscribe my name this 22nd day of October, A. D. 1918.

AXEL G. GULBRANSEN.
